UNITED STATES PATENT OFFICE.

CAP B. COLLINS, OF OAK PARK, ILLINOIS, ASSIGNOR TO COLLINS SAFETY RAZORS, OF CHICAGO, ILLINOIS, A COMMON LAW BUSINESS TRUST.

ROTARY RAZOR SHARPENER.

1,426,152.

Specification of Letters Patent. Patented Aug. 15, 1922.

Application filed June 7, 1919. Serial No. 302,476.

To all whom it may concern:

Be it known that I, CAP B. COLLINS, a citizen of the United States, residing at Oak Park, in the county of Cook and State of Illinois, have invented certain new and useful Improvements in Rotary Razor Sharpeners, of which the following is a specification.

Heretofore I have produced a rotary-10 razor having a circular disc blade revolved by a mechanical spring-motor contained in the handle of the device. In such apparatus the casing or shell, constituting a suitably-shaped handle, is composed of a pair of 15 matching or registering parts, the construction and connections being such that the manual turning of one of such handle elements relatively to the other winds up the motor.

20 The present invention concerns stropping or sharpening mechanisms for razors of this general type or style and does not necessarily relate to the razor itself, the improved sharpening device being wholly separate 25 from the razor and constituting an accessory or attachment applied thereto when stropping or sharpening of the blade is required. It is designed, however, so as to take advantage of the driving mechanism 30 for the razor-blade to temporarily operate the sharpening elements.

In order that those skilled in this art may have a full and complete understanding of this invention and its various structural 35 and functional advantages, I have illustrated a preferred and desirable embodiment of the same in the accompanying drawings forming a part of this specification and throughout the views of which like reference characters refer to the same parts.

In these drawings:

Figure 1 is a central vertical section through the razor and attached stropping device;

45 Figure 2 is a plan view of the structure of Figure 1; and

Figure 3 is a fragmentary side elevation showing the stropping appliance in its relation to the blade upon which it acts.

50 Referring to these drawings, it will be seen that the rotary-razor proper comprises a two-part handle 10, 11, the elements thereof unitedly or conjointly forming a general pear-shaped handle which conveniently fits 55 the hand both with respect to size and shape. Such handle contains a spring-motor 12 of

any suitable design or character controlled by a fly-ball governor 13 and adapted to be started or stopped by a brake mechanism actuated by a readily-accessible sliding button 14. The construction is such that the turning of the handle or casing element 11 winds up the spring of the motor. The latter, by means of suitable gearing, rotates a hollow-sleeve 15 having a bearing on a central stationary post 16, the end of the rotary sleeve having one or more notches 17 adapted to receive and form a driving connection with tongues 18 of the lower end of a sleeve or hollow shaft 19, also having bearings on the central post.

At its upper end sleeve 19 has an outstanding circular flange 20 supporting a flat apertured blade-supporting member 21, the round, sharp-edged disc-blade 22 being held 75 against and hence driven or rotated by the member 21 by a dished blade-clamp 23 provided with a plurality of apertures 24 and mounted on an externally-threaded screw 25 adapted to be screwed into the upper 80 threaded end of the rotary sleeve 19. Thus, this tube rotates with the sleeve and forms a bearing for the latter on the upper portion of post 16. Beneath the blade is a stationary, round, toothed face-guard 26, and 85 when in use the razor is equipped with a round dished face-plate (not shown) above the blade-clamp 23, and held in place by a threaded stem thereon screwed into a socket 27 in the upper end of post 16. When the 90 stropper is to be used, however, such face-plate and its stem are temporarily removed and consequently are not shown in Figure 1. The parts of the appliance so far described are not new in so far as this patent 95 application is concerned, the present invention residing solely in the demountable stropping appliance about to be described and its association with the razor.

Such sharpening apparatus comprises a 100 tubular support 30 internally affording a bearing for a hollow hub 31 of a horizontal bevel-gear 32 having one or more lugs 33 on its under side adapted to fit in the apertures 24 of the revoluble blade-clamp 23, thereby 105 forming a driving connection between the latter and the former. As is illustrated, the gear is permanently rotatably secured to the element 30 by a collar or washer 34 fastened to the upper protruding end of the gear-hub 31 and overlying the top surface of part 30. To hold the stropping device in position on

the razor, a screw 35 is threaded into the socket 27, such screw having a knurled handle or thumb-piece 36 at one end and an unthreaded intermediate section 37 constituting a support and bearing for the hub gear 31. By means of this screw the whole unitary stropping device is demountably or detachably associated with the razor.

A stud-shaft 38 is fixed in a recess of and projects laterally from the supporting member 30 and revoluble on such shaft I provide a sleeve 39 to which is secured a bevel-gear 40 in mesh with gear 32 and a spur-gear 41. A downwardly-bent frame 42 has two spaced parts 43 and 44 rockingly mounted respectively on the shaft between the elements 30 and 40 and on the sleeve between the members 40 and 41. Such skeleton frame affords bearings for a shaft 45 provided at one end with a spur-gear 46 in mesh with gear 41 by means of which the shaft is rotated and at its other protruding end with a disc-shaped, circular, leather-stropper 47 held in position between two discs or collars 48 and 49 and adapted to engage the upper side of the edge of the razor-blade 22.

A supplemental or auxiliary frame 50 is hinged to the main-frame 42 on a pin 51, a coiled torsion-spring 52 encircling such hinge-pin and having its ends bent around the parts of the two frames, whereby the lower or complementary one tends to swing upwardly. Frame 50 carries a rotary shaft 53 driven by a gear 54 thereon in mesh with gear 46, the shaft having a leather-stropping-disc 55 adapted to be accommodated between adjacent teeth of the face-guard 26 and to act transversely on the under side of the edge of the blade 22 a short distance to one side of the complementary stropping-disc 47.

The operation of this appliance is substantially as follows:

The razor face-plate and its screw-threaded shaft, referred to above but not shown, having been removed from the razor, and the stropping-appliance having been applied thereto and held in place by screw 35 with the two disc stroppers or sharpeners engaging opposite sides of the circular edge of the blade in offset or staggered relation, and held pressed thereto by spring 52, the operator winds up the razor motor 12 by turning part 11 of the shell of the handle and sets the appliance upright, as shown. As will be readily understood, the motor not only rotates the blade 22 in the usual way, but it also revolves both stropping discs at the same time through the gearing specified by rea-

son of the clutch connection 17, 18 and all 60 portions of the razor's edge are successively and progressively acted upon by the pair of rotating stroppers, the blade making as many revolutions as may be necessary to thoroughly and keenly sharpen its edge. When 65 the stropping operation has been completed, if the motor has not run down, it may be stopped by manipulation of the key 14. Then the entire stropping apparatus is removed or detached and the face-plate replaced, whereupon the sharpened razor is ready for use.

It is to be understood that the invention is not limited and restricted to the precise and exact structural details specified because 75 these may be varied within comparatively wide limits without departure from the heart and essence of the invention and without the sacrifice of any of its substantial benefits and advantages.

I claim:

1. A stropping attachment for razors comprising in combination a stropping-element, means to revolve said element, and means to detachably secure said attachment to a razor 85 having blade-rotating means with said element revolving means operatively connected to said blade revolving means, whereby the latter actuates the former to stop the blade during its rotation.

2. A stropping attachment for razors comprising in combination a pair of stropping elements, means to revolve said elements, and means to detachably secure said attachment to a razor having blade-rotating means 95 with said element revolving means operatively connected to said blade rotating means and with the stropping elements engaging the opposite sides of the edge of the blade, whereby the blade-rotating means actuates the element revolving means to stop the blade on both sides of its edge simultaneously during the rotation of the blade.

3. A stropping attachment for razors comprising in combination a pair of stropping elements in offset relation, means to revolve said elements, and means to detachably secure said attachment to a razor having blade rotating means with said element revolving means operatively connected to said blade-rotating means and with the stropping elements engaging the opposite sides of the edge of the blade, whereby the blade-rotating means actuates the element revolving means to stop the blade on both sides of its edge 115 simultaneously during its rotation.

CAP B. COLLINS.
